(57) CLAIM

The ornamental design of a novelty garment, as shown and described.

DESCRIPTION

FIG. 1 is a front, right, and top perspective view of a novelty garment according to the design;

FIG. 2 is a front elevation view thereof;

FIG. 3 is a rear elevation view thereof;

FIG. 4 is left side elevation view thereof;

FIG. 5 is a right side elevation view thereof;

FIG. 6 is a top plan view thereof;

FIG. 7 is a bottom plan view thereof; and,

FIG. 8 is front, right and bottom perspective view shown in use.

The broken lines depict environment that forms no part of the claimed design.

1 Claim, 5 Drawing Sheets
